Primary Examiner — Abraham Bahta(74) *Attorney, Agent, or Firm* — Marshall, Gerstein & Borun LLP(57) **CLAIM**

The ornamental design for a collapsible container, as shown and described.

DESCRIPTION

FIG. 1 is a perspective view of the collapsible container showing my new design;

FIG. 2 is a front view, the back view being a mirror image thereof; and,

FIG. 3 is a left side view, the right side view being a mirror image thereof.

The broken lines are for illustrative purposes only and form no part of the claimed design.
